UNITED STATES PATENT OFFICE.

CHARLES E. GODLEY, OF DETROIT, MICHIGAN, ASSIGNOR TO EDMUNDS AND JONES CORPORATION, OF DETROIT, MICHIGAN, A CORPORATION OF NEW YORK.

LAMP-MOUNTING.

1,270,940.

Specification of Letters Patent.

Patented July 2, 1918.

Application filed January 23, 1917. Serial No. 142,083.

To all whom it may concern:

Be it known that I, CHARLES E. GODLEY, a citizen of the United States, and residing at Detroit, in the county of Wayne and State 5 of Michigan, have invented a new and Improved Lamp-Mounting, of which the following is a specification.

This invention relates to means for so supporting projecting lamps such as headlights, 10 searchlights and spot-lights, as to permit them to be swung in any desired manner and the rays of light therefrom to be projected in substantially every direction, and its object is to provide a lamp mounting for this 15 purpose which will be simple, strong and durable, and which can be manufactured at comparatively low cost.

This invention consists in combination with a lamp, of a stationary support having 20 a bearing in which a curved member is revolvably mounted, this member having a bearing at its outer end, a lamp mounted in the bearing at the outer end, the bearing consisting of a cylindrical member extending 25 into a split sleeve and a collar to cause the sleeve to grip the cylindrical member.

In the accompanying drawings, Figure 1 is an elevation of a searchlight mounted on an upright rod by means of this improved 30 mounting. Fig. 2 is a vertical section of this mounting. Fig. 3 is a plan thereof. Figs. 4 and 5 are sections on the lines 4—4 and 5—5 of Fig. 2. Fig. 6 is a side elevation of a searchlight mounted on a base. 35 Fig. 7 is a vertical section thereof through the bearing for the lamp. Fig. 8 is a section on the line 8—8 of Fig. 7.

Similar reference characters refer to like parts throughout the several views.

40 The lamp body 1 shown in Figs. 1 to 5, inclusive, is provided with a hollow trunnion or hub 2 having a circumferential groove 3. The supporting clamp 4 is shown provided with a stiffening rib 5 and parallel ribs 6 by which an upright rod or bar 7 may be engaged. A bent rod 8 is slidable in a proper hole in the clamp member 4. A nut on the rod forces the end 9 against the upright 7, which end has a groove 10 which 45 receives this rod or bar. It will be understood, however, that I am not confined to this form of clamping device, as any other desired construction of support may be employed. A hollow hub or trunnion 12 hav-

ing a groove 13 is connected to this support 55 ing member.

The member connecting these trunnions is in the form of a hollow elbow 15 having its arms or branches ending in sleeves fitting over the hubs 2 and 12 and having tapering rings or seats 16 and threaded ends 17. The sleeves that embrace these hubs are formed with slits 18 as shown in Figs. 4 and 5 so that they may be caused by the collars 19 and 20 to firmly grip the hubs. 60 These collars have tapering seats 22 that fit the rings 16 and are also formed with threaded portions 23 that engage the threaded ends 17 of the split sleeves of the elbow. These collars are forced up onto the sleeve-ends of 65 the branches of the elbow by means of the screw threads to a greater or less extent and the grip of the split sleeves on the hubs is greater or less in proportion thereto. The lamp 1 can therefore be swung around the 70 vertical axis of the hub 12 and around the horizontal axis of the hub 2 and will be held in any desired position by the friction between the hubs and the elbow.

The screws 27 extend into the grooves 3 80 and 13 and prevent the hubs from slipping out of the sleeves. The support 7 will prevent the lamp from being swung entirely around on the hub 12 in either direction and thus will prevent the wires 26 from being 85 twisted too far. In order to prevent the lamp from being swung entirely around on the axis of the hub 2 a small key 29 is mounted in the hub 2 across the groove 3 therein, against which key the screw 27 in that end 90 of the elbow will contact when the lamp is swung in either direction. This again will prevent the wires 26 from being twisted off. The collars may have openings 28 through 95 which the screws are inserted and adjusted.

It is apparent that the revoluble member may be forked and carry a bearing at the end of each branch. In Figs. 6, 7 and 8, the base or support 31 is provided with a split sleeve 32 provided with a screw 33 that enters the groove 34 in the cylindrical extension 35 of the fork 36. The base 31 and one of the arms of the fork 36 as well as its hub are hollow to permit the cable 37 to pass to the lamp. A collar 40 on the split sleeve 100 32 is adapted to cause it to grip the hub 35 as before described.

Formed on or secured to the end of these

arms of the fork are two hubs 38 and 39, one of which is hollow. A split sleeve 41 is connected to each side of the lamp body 42 and receives one of the hubs. The collar 43 on each split sleeve is adapted to force it to grip the hub as before described. The lamp may be swung by means of a handle 44 formed on the body of the lamp.

I claim:—

10. 1. In a lamp mounting, the combination of a cylindrical circumferentially-grooved hub on a lamp body, a second cylindrical circumferentially-grooved hub on a supporting member, an elbow having a sleeve at each end fitting over each of the hubs, a screw carried by each sleeve and extending into the groove of the adjacent hub, and means to cause the sleeves to grip the hubs.
15. 2. In a lamp mounting, the combination of a cylindrical circumferentially-grooved

hub on a lamp body, a second similar hub on a supporting member, a tubular connecting member between the two hubs provided with a socket in each end to receive the hubs, a screw mounted in the wall of each socket 25 and extending into the groove in the hub within the socket, and means extending across the groove in one of the hubs to limit the rotation of the connection relative to said hub.

30. 3. In a lamp mounting, the combination of a cylindrical circumferentially-grooved hub on a lamp body, a support for the lamp body having a split sleeve fitting over said hub and provided with external threads, a screw mounted in said sleeve and extending into the groove in the hub, and a collar screwed onto the sleeve and extending over said screw.

CHARLES E. GODLEY.
